UNITED STATES PATENT OFFICE

JAMES C. TRAVILLA, JR., OF PHILADELPHIA, PENNSYLVANIA, ASSIGNOR TO GENERAL STEEL CASTINGS CORPORATION, OF GRANITE CITY, ILLINOIS, A CORPORATION OF DELAWARE

TANK VEHICLE UNDERFRAME

Application filed June 13, 1931. Serial No. 544,185.

This invention relates to railway rolling stock and consists in a novel vehicle underframe and particularly the end construction thereof adjacent the draft gear. In the usual water bottom tender underframe, for example, a double draw bar pocket is formed beneath the front end sill and extends rearwardly thereof and the walls of the pocket form a portion of the wall of the water containing compartment of the underframe. If any leaks develop in this portion of the tank wall, they must be repaired through the draw bar pockets. These pockets are comparatively narrow and, consequently, access to the tank wall through them is difficult.

The main object of the present invention is to construct a water bottom underframe in which the walls of the draw bar pockets form no part of the tank wall and in which the portions of the tank wall adjacent the draw bar pockets are readily accessible for the purpose of repairing leaks.

These objects and others are attained in the structure illustrated in the accompanying drawings in which—

Figure 1 is a top view of a portion of a tender frame embodying the invention.

Figure 2 is a side view of the same.

Figure 3 is a vertical longitudinal section taken on the longitudinal center line of Figure 1 and shows a portion of the floor of the coal bunker and of the front wall of the water tank beneath the bunker.

Figure 4 is a front view of the structure shown in Figure 1.

Figure 5 is a vertical transverse section taken on the line 5—5 of Figure 1.

I illustrate my invention as applied to a one piece waterbottom tender underframe which includes side sills 1, center sills 2, intermediate sills 3, transoms 4, and an end sill 5. A horizontal web 15 having perforations 15a to facilitate casting, extends between the tops of the center sills. A pocket 6 for a buffing device 7 is located forwardly of the center of the end sill 5, and members forming a double draw bar pocket 8, 9 depend from the bottom web 10 of the underframe casting and extend rearwardly of sill 5. A diagonal rib 20 supports and braces

the rear portion of the draw bar pockets from web 10.

Horizontal bottom web 10 and the side and end sills 1 and 5, respectively, are preferably cast integral and are imperforate whereby the entire casting serves as a tank bottom member to which tank side and end sheets 21 and 22 are secured. An opening 11 is provided in web 10 for connection with a conduit leading to the boiler of the engine.

Immediately above the draft pockets 8, 9, web 10 is recessed as indicated at 10a and upright webs 12 and 13 extend around recess 10a and with end sill 5 form a box shape member which serves to exclude water from the portion of the casting immediately adjacent the draft pockets. Horizontal and vertical draw bar pocket walls 8a, 18, and 19 are spaced from webs 12 and 13 of the tank. The front portion of the coal bunker floor 16 is supported above the draw bar pockets upon upright plates 17 and 18 which are welded to top web 15 in alignment with webs 12 and 13, respectively, and which form a recess R in the tank front wall. Access may be readily had through this recess and through opening 14 in top web 15 to the portions of the water compartment of the underframe immediately adjacent the draw bar pockets.

In practice the invention does not materially decrease the capacity of the vehicle from that of the usual construction since the water containing portions of the underframe extend forwardly on each side of the pockets to the end sill. Obviously, the necessity of gaining access through the draw bar pockets for the purpose of caulking leaks is eliminated as the tank walls at all points are spaced substantially from the draw bar pocket walls and underframe webs 12 and 13 are easily accessible from the top through opening 14 and the recessed front sheet of the superstructure, or from the bottom on either side of rib 20 through opening 10a.

While I have illustrated the invention as applied to a water-bottom tender underframe, the principles thereof might be readily embodied in any other type of underframe in which it is desired to separate a

fluid chamber or passage from an adjacent draft pocket. The invention, of course, is not limited to the exact details illustrated, but may be modified in various other ways, as will be apparent to those skilled in the art, without departing from the spirit thereof, and I contemplate the exclusive use of all such modifications as come within the scope of my claims.

I claim:

1. In a railway vehicle underframe, a draw bar pocket, and underframe elements forming walls, a fluid compartment extending around the sides and rear of said pocket, the adjacent walls of said pocket and compartment being spaced apart to provide access between them to said compartment walls for inspection and repair purposes.

2. In a railway vehicle underframe, a draw bar pocket, and a fluid compartment wall formed in the underframe at the rear of said pocket, the adjacent walls of said pocket and compartment being spaced apart to provide access between them for inspection and repair purposes.

3. In a railway vehicle underframe, a fluid compartment formed in part by underframe elements, and a draw bar pocket extending inwardly at the lower portion of an end of said underframe, said compartment extending on opposite sides of said pocket and the walls of said pocket being spaced from the walls of said compartment a sufficient distance to permit access from outside said pocket to the portion of said compartment wall adjacent said pocket.

4. In a railway vehicle underframe, a draw bar pocket having vertical and horizontal walls, a liquid compartment formed in part by underframe elements at the rear of said pocket and extending forwardly at the sides of said pocket and having vertical end walls and a substantially horizontal bottom web plate, said draw bar pocket walls being spaced from said liquid compartment walls and web plate so as to provide access to said latter walls and web plate.

5. In a railway vehicle underframe, an end sill, a draw bar pocket having vertical and horizontal walls extending below and rearwardly of said end sill, and a liquid compartment having vertical end walls and a bottom web plate formed by underframe elements, said draw bar pocket walls being spaced from said liquid compartment walls and web plate to provide access to said latter mentioned walls and web plate.

6. In a railway vehicle underframe, an end sill, a draw bar pocket extending inwardly beneath said sill, and a fluid compartment wall formed by underframe elements and extending inwardly from said sill on at least one side of said pocket, all of the walls of said pocket being spaced from the walls of said compartment.

7. In a railway vehicle underframe, an end sill, an imperforate underframe bottom plate serving as a wall for a fluid compartment, a recess in said plate adjacent said sill, upright webs extending around said recess and serving to exclude fluid from said recess, and a draft pocket extending from said sill into said recess and having horizontal and vertical walls, said walls being spaced from said webs and bottom plate.

8. In a railway vehicle underframe, an end sill, an imperforate bottom plate serving as a wall for a fluid compartment, a recess in said plate adjacent said sill, upright webs extending around said recess and serving to exclude fluid from said recess, a draft pocket extending from said sill into said recess and including horizontal and vertical walls, said walls being spaced from said webs and bottom plate, and a rib supporting the inner end of said pocket from said plate.

9. In a railway vehicle underframe, an end sill, a draw bar pocket extending inwardly beneath said sill and having vertical and horizontal walls, and a fluid compartment extending on opposite sides of said pocket and including upright end members, each spaced from the walls of said pocket, the top of the underframe between said end sill and said members being open to permit access to said members.

10. In a railway vehicle underframe, an end sill, a draw bar pocket extending inwardly beneath said sill and having vertical and horizontal walls, a fluid compartment extending on opposite sides of said pocket and including upright end members, each spaced from the walls of said pocket, the top of the underframe between said end sill and said members being open, and super-structure mounted on the underframe and spaced above said end sill a sufficient distance to permit access to said end members.

11. In a railway tank vehicle underframe, an end sill, a draw bar pocket extending inwardly beneath said sill, a fluid compartment extending on opposite sides of said pocket and including upright end members, each spaced from the walls of said pocket, the top of the underframe between said end sill and said members being open, and additional upright plates forming an open pocket above said vertical members, said upright plates constituting portions of the tank wall.

12. In a railway tank vehicle underframe, an end sill, a draw bar pocket extending inwardly beneath said sill, a fluid compartment extending on opposite sides of said pocket and including upright end members, each spaced from the walls of said pocket, the top of the underframe between said end sill and said members being open, additional upright plates forming an open pocket above said upright members and constituting portions

of the tank wall, and a coal bunker mounted on said additional plates.

13. In a railway vehicle, an underframe including a fluid compartment, an end sill, 5 and a draw bar pocket extending inwardly beneath said sill, and super-structure including tank side and front sheets secured to said underframe and a coal bunker, said front sheets including a depressed part above said 10 draw bar pocket, said part being spaced from said pocket and co-operating with said bunker to exclude fluid from the walls of said pocket, and also forming a passage above said end sill through which access may be had 15 to the portions of said underframe adjacent said draw bar pocket.

In testimony whereof I hereunto affix my signature this 6th day of June, 1931.

JAS. C. TRAVILLA, JR.
